ARTHUR J. BRIGGS, OF SYRACUSE, NEW YORK, ASSIGNOR TO REMINGTON TYPE-WRITER COMPANY, OF ILION, NEW YORK, A CORPORATION OF NEW YORK.

TYPE-WRITING MACHINE.

1,242,419.

Specification of Letters Patent.

Patented Oct. 9, 1917.

Application filed August 28, 1916. Serial No. 117,257.

To all whom it may concern:

Be it known that I, ARTHUR J. BRIGGS, citizen of the United States, and resident of Syracuse, in the county of Onondaga and State of New York, have invented certain new and useful Improvements in Type-Writing Machines, of which the following is a specification.

My invention relates to typewriting machines and more particularly to the carriage feed mechanism of such machines. Said mechanism is shown in the present instance incorporated in a typewriting machine which, considered as a whole, has combined therein in an unusual degree the characteristics of merit and low cost of manufacture, and it is the principal object of the present invention to produce a carriage feed mechanism having these characteristics.

To the above and other ends which will hereinafter appear, my invention consists in certain features of construction and combinations and arrangements of parts, all of which will be fully set forth herein and particularly pointed out in the claims.

In the accompanying drawings,

Figure 1 is a front to rear vertical sectional view upon an irregular section of as much of the complete machine as is necessary to illustrate the embodiment therein of the present invention.

Fig. 2 is a rear elevation of the same.

Fig. 3 is an enlarged perspective view of the carriage feed mechanism as seen from the back, and

Fig. 4 is a perspective view of parts of said mechanism as seen from the front.

In all of the views parts have been omitted or broken away or shown in section, as has been found convenient.

It will be understood that the present invention is capable of embodiment in whole or in part, in machines differing in many respects from that shown in the drawings.

The main frame of the machine illustrated comprises a casing having a base portion 1, surmounted by a vertical flange or wall 2, which extends around three sides of a rectangle and a short distance across the back of the machine at each side, and said frame also comprises right-and-left-hand top plates 3. Said frame also includes a main casting comprising a carriage rail 4 and a type bar segment 5. Said casting also comprises two side posts 6 and a cross bar 7

in the base of the machine, where said casting is fastened to the base 1 by means of screws 8.

The frame also comprises a cross bar 10, said bar consisting of a separate casting 60 suitably secured in the base 1. Said frame is more fully shown and described and is claimed in my application for Letters Patent filed August 28th, 1916, Serial No. 117,261.

The type action comprises printing keys 11 mounted on the forward ends of key levers 12 which are pivoted on a wire 13 seated in the cross bar 7, which bar is slotted along its under edge to guide the key 70 levers. Each of the key levers has a depending arm 14 to which is connected a restoring spring 15 and all of said springs are secured to a channel bar 16 in the base of the machine. A series of sub-levers 17 of bell-crank form are guided in slots in the cross bar 10 and pivoted on a pivot wire or rod 18. Each of said bell-cranks has a forwardly extending arm carrying a headed pin 20 which plays in a slot 21 in the forward 80 part of a key lever 12. Each of said sub-levers is connected by a link 22 with a front strike type bar 23 carrying a type 24. Said type bars are pivoted on a wire 25 suitably laid in the type bar segment 5, the forward 85 face of which is slotted to guide the type bars. The types 24 are adapted to strike against the front face of the platen 26 which is mounted in a carriage 27 having the form shown in Figs. 1 and 2, that is to say, it has 90 two grooved rails for the accommodation of antifriction balls 28, one of said rails being horizontally in front of the other. The rail 4 has its forward face grooved to match the forward rail of the carriage and a 95 grooved rail 30 is secured to the rear face of the bar 4 to coöperate with the rear ball or balls 28. The rail 30, as here shown, is made of sheet metal with sufficient resiliency to obviate the necessity of any relative adjustment of the several carriage rails.

The carriage is shown propelled toward the left by means of a cord 31 wound on a spring drum 32 mounted on a branch of the left-hand post 6 of the main casting.

The carriage has rigidly mounted thereon, at its rear part, a feed rack 33 which meshes with a pinion 34 formed rigid with an escapement wheel 35. Said pinion and wheel are fast on the rear end of a shaft 110

36 which is journaled in the rail part 4 of the main casting, in a manner which will be more particularly described hereinafter.

A universal bar 37 is operated by the type 5 bars near the pivotal ends of the latter and said universal bar consists of a segment-shaped channel bar of sheet metal mounted above and within the type bar segment 5 in position to be struck by suitably flattened

10 portions 38 of the several type bars. Said universal bar is mounted on and wholly supported by the front of a sheet metal plate or frame 40 to which it is secured as by rivets 41. The frame or plate 40 has a flat 15 part lying horizontally beneath the rail 4 and its forward end is suitably bent to conform to that part of the universal bar 37 which is secured to it. The plate 40 near its forward part is of substantial width and 20 it has bent up therefrom two ears 42, one at the right and one at the left edges thereof and these ears are pivoted at 43 to the upstanding arms 44 of a bail or yoke frame, which frame comprises a connecting bar 45 25 extending in a right and left-hand direction beneath the plate 40. Between said cross bar and said plate a rod 46 extends through the arms 44 and constitutes the pivot of the bail or yoke frame, to which end said 30 rod also extends through vertically disposed parts of a stationary frame or bracket 47 which is secured by means of screws 48 to the under side of that part of the main casting which also constitutes the carriage rail 4. 35 It will be seen that the bail 44, 45 is mounted on two pivots spaced a sufficient distance apart in a right-and-left-hand direction to insure that both ends of the universal bar shall move alike. The rod 46 is here shown 40 with a small head on one end and its other end split and spread after the fashion of a cotter-pin to retain it in place.

In rear of the forward pivots just above described the plate 40 has an ear 50 bent up therefrom so as to stand in a fore and aft vertical plane, and this ear constitutes one of the dogs of the escapement, its upper rear corner standing normally as shown in Figs. 1 and 2, a little in front of the escapement wheel 35 and in such position that when the universal bar is moved toward the rear this dog passes between two of the teeth of the escapement wheel. This vertical ear is also utilized as a support for the 55 rear part of the plate 40, to which end said ear is pivoted at 51 to the prolonged upper end of an arm 52 of a bail, which bail also comprises a horizontal bar 53, Fig. 2, and a second arm 54 shorter than the arm 52. 60 Above the cross bar 53 the arms 52, 54 are pivoted on a rod or wire 55, which rod also passes through ears 56 bent up from a rearward extension of the bracket 47. The bail bar 53, as here shown, is much shorter than the forward bail bar 45, and the former bail 65

is connected with the plate 40 at only one point, 51, instead of at two, as in the case of the forward bail. It will be seen that the universal bar has a three-point support of such character as to cause it to move substantially directly toward the rear when struck by a type bar, and of such character as to guide it for parallel and equal motion in all its parts.

The bracket 47 is struck up out of a single 75 piece of sheet metal and comprises a flat horizontal part of irregular outline, as shown, and two end pieces bent up vertically and thence horizontally, forming horizontal ears through which the screws 48 pass. The 80 right-hand vertical part of this bracket has an arm 57 projecting inwardly therefrom and the universal bar plate 40 has an ear 58 at the rear end, which is connected with the arm 57 by a spring 60 tending to draw 85 the universal bar toward the front of the machine and constituting the restoring spring of the escapement mechanism.

It will be perceived that the universal bar is supported entirely by the sheet metal 90 plate 40, which has an ear 50 bent up therefrom and constituting one of the feed dogs of the escapement, and that said plate 40 is supported by the bracket 47. As will more fully appear hereinafter the entire 95 escapement mechanism, except the escapement rack or wheel, is supported by this bracket 47, and can be removed from the machine by removing the two screws 48. This mechanism, including the universal bar 100 itself, is assembled outside of the machine in the process of manufacture and is placed in position in the machine as an entirety.

The second escapement dog 61 is pivoted, by a pivot 62, to an ear 63 bent up from the rear end of the plate 40 so that it stands in a vertical transverse plane. The dog 61 has a tooth 64 bent off therefrom into a fore and aft vertical plane, and said tooth engages the teeth of the escapement wheel 35. 110 This tooth 64 stands, as seen in Fig. 1, just at the rear of the dog 50, and, as seen in Fig. 2, it is off-set from the dog 50 to a sufficient extent to enable said dog 50, when the universal bar is moved toward the rear 115 of the machine, to move into position to engage the next tooth of the wheel 35 succeeding the one just released by the tooth 64. The relation of these two escapement dogs can, of course, be varied, but, as here 120 shown, the carriage is adapted to have a little more than a half drop on the positive stroke of the universal bar, the step being completed upon the return stroke of the universal bar.

As far as the operation of the escapement in giving step-by-step feed to the carriage is concerned the escapement dog or tooth 64 could be integral with the plate 40, but I have shown said dog pivoted on the pivot 125

62 in order to enable the carriage to be released by moving said dog out of the wheel and also in order to enable the carriage to be pulled back to the right in which operation the dog 61, 64 has the action of a pawl, yielding to the teeth of the wheel and snapping in behind them. To this end the dog is controlled by a wire spring 65, which is secured to the under side of the plate 40 by means of a screw 66, Fig. 1, and which passes through a hole in a depending arm of the dog 61, the tension of said spring being exerted toward the observer's right in Figs. 2 and 3. The motion of the dog under the impulse of said spring is limited by an arm 67 of said dog striking against the under side of a projection 68 of the ear 50 of the plate 40.

A space key or bar 70 of the usual form occupies the usual position at the front of the keyboard and said space bar is mounted by means of brackets 71 on the transverse front bar 72 of a U-shaped or bail-shaped frame which also includes two long levers 73 extending to the back of the machine and each of them having a depending part which is pivoted on the same wire or rod 18 that constitutes the pivot of the sub-levers. The space bar and its frame are controlled by two restoring springs 74 each connected at 75 to one of the levers 73 and each also connected to the stationary framework. Suitable padded stops 76 mounted on the front part of the frame, act to limit the upward and downward motion of the space bar, said stops playing between parts of the base 1.

Each of the levers 73 has at its rear end a laterally projecting pin 77, and said pins lie behind inclined cam arms 78 depending from a rock shaft or pivoted frame 80. This frame consists essentially of an angle-bar lying across the back of the machine and at each end having an ear 81 bent up therefrom and into said ears are threaded or otherwise secured pins 82 which pass through sheet metal brackets 83 suitably mounted on lugs of the main casting 6, 7. At its middle the bar 80 has projecting upward therefrom an arm 84, the upper end of which passes through a slot in the horizontal part of the plate 40 as will be understood from Fig. 1. The whole construction is such that if the space bar 70 be depressed the pins 77 moving upward will rock the arms 78 toward the front of the machine, and the arm 84 toward the rear of the machine thus operating the escapement; and if said escapement be operated by the type bars then the arm 84 and bar 80 will be rocked but without affecting the space bar 70. The bar 80, in actual practice in the particular machine shown in the drawings, is also utilized to feed the ink ribbon, but this is not shown nor claimed herein. As shown in the present instance the arm 78 and ears 81 are integral

parts of the angle bar 80, which angle bar is stamped out of sheet metal and bent up into the form shown. The arm 84 is shown composed of two parts, the lower part of which is integral with the bar 80 and the upper part of which is riveted thereto, but it will, of course, be understood that all of this construction can be varied.

The carriage release mechanism includes a release key or finger piece 85, Figs. 1 and 3, consisting of a bent-off and suitably formed part of a long sheet metal bar 86 mounted for sliding motion on the back of the carriage 27. As shown in the present instance this bar has a flange 87 bent off toward the rear from its lower edge, partly to stiffen the bar and partly to furnish a wider contacting surface for the co-operating part. The bar 86 has two parallel slots 88, one near each end and both inclined upward and toward the operator's left, and through these slots extend headed pins 90, the forward ends of which are secured in brackets or ears 91 of the carriage 27. A spring 92 pulls the bar 86 toward the operator's left, the left-hand end of said spring being connected with an ear 93 projecting upward from the carriage. The construction is such that the bar normally occupies its left-hand and upper position. Pressure on the finger piece 85 moves the bar toward the left and downward, all parts of the bar moving downward to the same extent. Said bar 86 operates a lever 94 which is pivoted at 95 on a bracket 96 consisting of a branch of the right-hand one of the two vertical parts of the stationary bracket 47, the bracket 96 being bent into a transverse plane and extending upward behind the wheel 35. The lever 94 is here shown with three arms, one of which extends from the pivot 95 upward and toward the operator's right, being thence bent toward the front of the machine forming an ear 97 which lies under the flange or rib 87 of the bar 86 in such position that when said bar is moved downward by an operation of the finger piece 85 the said ear will be moved downward and the lever 94 will be rocked toward the operator's right. The ear 97, as here shown, has a lug 99 projecting therefrom. The lever 94 also has a downward extending arm having an ear 98 bent off therefrom toward the rear of the machine and this ear is adapted to operate an arm 100 of the feed dog 61, said arm extending upward from the pivot of said dog, and being bent toward the rear of the machine as shown.

The whole construction is such that when the finger piece 85 is operated the lever 94 is rocked and the dog 61 is depressed against the tension of the spring 65 out of engagement with the wheel 35 and the carriage can then be moved to an indefinite extent in either direction, the bar 86 sliding over the 130

ear 97. When the finger piece is released the bar 86 is restored by its spring 92, the dog 61 is restored by its spring 65 and the lever 94 is restored to normal position by a weight 101 mounted on a horizontal arm of said lever. The ear 98 is of such length in a front and back direction as that it does not lose control of the arm 100 at any time during the vibration of the universal bar 10 and feed dogs. As here shown the dog 61, lever 94 and bar 86 are all stamped up out of sheet metal, making them very inexpensive to manufacture and at the same time they are sufficiently substantial and are efficient in use.

The machine as here shown is equipped with a ribbon vibrator 102 consisting of a suitably formed ribbon guide standing in front of the platen and having a long stem, the lower end of which is pivoted at 103 on a lever arm 104, Fig. 1. This lever arm is integral with the bail 52, 53, 54, and it consists simply of a forward prolongation of the cross bar 53 of said bail, said prolongation having an ear 105 bent up therefrom and through which the pivot pin 103 passes. The vibrator 102 has ears 106 bent off therefrom and coöoperating with a stationary guide plate 107 which is secured by means of screws 108 to the front face of the part 4 of the main casting. The stem of the vibrator 102 passes through a hole 109 in the plate 40. This ribbon mechanism is not claimed herein but is claimed in another application filed August 28th, 1916, Serial No. 117,258. The guide plate 107, however, performs a function in connection with the escapement mechanism as follows: The shaft 36 of the escapement wheel 35 is reduced where it enters the casting 4 so that just at the rear of said casting there is a shoulder on the shaft which prevents motion of the shaft toward the front of the machine. Said shaft passes entirely through the casting 4 and near its forward end it is formed with a groove 110 and the plate 107 is formed with a notch 111 which engages in said groove and prevents endwise motion of the shaft 36. The construction is such that when the machine is assembled this shaft is held against endwise motion but with freedom to turn, but upon removing the guide 107 by loosening the two screws 108 the shaft is then free to be slipped out of its bearing toward the rear and thus removed from the machine. It will be perceived that the construction is very simple and inexpensive and that it is one that can be assembled with a minimum of labor and trouble. In this last operation the escapement wheel shaft is simply thrust into its bearing opening from the rear and the ribbon guide is put in place and fastened by the two screws 108 which thus hold in place said guide, the upper end of the ribbon vi-

brator and the escapement wheel and its shaft and pinion.

It will be noted that the universal bar and its supporting plate 40 are of inexpensive construction, that they are light and easily operated, that they are accurately guided so as to be free to move in the direction in which they should move in operation and yet are rigid against the action of the escapement wheel, and that their construction is such as to make the parts easily assembled and easily removed from the machine. In short, the construction is at once good and inexpensive, and the same is true of the space key and releasing mechanisms.

Various changes can be made in the details of construction and arrangement without departing from my invention.

What I claim as new and desire to secure by Letters Patent, is:

1. In a typewriting machine, the combination with front strike type bars; of a universal bar in position to be operated by said type bars, a frame on which said universal bar is supported, oscillatory frames pivoted to said supporting frame and guiding it for parallel and equal motion in all its parts, feed dogs carried by said supporting frame, and a rack.

2. In a typewriting machine, the combination of a supporting frame mounted for bodily motion front and back, a universal bar wholly supported by the front part of said frame, and a feed dog wholly supported by the rear part of said frame.

3. In a typewriting machine, the combination with the carriage; of a horizontal reciprocatory frame beneath the carriage, a rocking frame having two arms at a distance apart and each pivoted to said reciprocatory frame, a third arm pivoted to said reciprocatory frame, the three said arms acting to support said reciprocatory frame, a segmental universal bar carried by a forward projection of said reciprocatory frame, and a feed dog also carried by said reciprocatory frame.

4. In a typewriting machine, the combination of a bracket detachably mounted on the main framework; a reciprocatory frame mounted in said bracket for bodily motion front and back; a segmental universal bar carried by said reciprocatory frame; and a feed dog also carried by said reciprocatory frame; the construction being such that said frame, universal bar, dog and bracket can be removed from the machine as an entirety.

5. In a typewriting machine, the combination with front strike type bars, a carriage and an escapement rack; of a stationary bracket detachably mounted beneath the carriage; a rocking frame pivoted to said bracket; a horizontal plate mounted on said rocking frame for bodily motion front and back, and having an extension toward the

front of the machine; a segmental universal bar carried by said extension in position to be operated by said type bars; and means carried by the rear part of said plate for 5 coöperation with said escapement rack.

6. In a typewriting machine, the combination with type bars, of a sheet metal plate mounted for bodily reciprocation, a universal bar carried by said plate and in 10 position to be operated by said type bars, a feed dog consisting of an ear bent up from said plate, and a second feed dog pivoted to said plate.

7. In a typewriting machine, the combination with front strike type bars, a carriage and an escapement rack; of a stationary bracket detachably mounted beneath the carriage; a rocking frame pivoted to said bracket; a horizontal plate mounted on said 20 rocking frame for bodily motion front and back, and having an extension toward the front of the machine; a segmental universal bar carried by said extension in position to be operated by said type bars; means 25 carried by the rear part of said plate for coöperation with said escapement rack; a lever pivoted on said bracket in position to move said means out of engagement with said rack; and a hand operated bar on said carriage coöperating with said lever.

8. In a typewriting machine, carriage feed mechanism comprising a universal bar, a sheet metal plate constituting the support for said universal bar and having an ear 35 bent up therefrom and constituting an escapement dog; a space key; and a lever operated by said space key and having an arm thereof engaging said plate.

9. In a typewriting machine, the combination with front strike type bars, of a universal bar in position to be operated by said type bars; a frame on which said universal bar is supported; oscillatory frames pivoted to said supporting frame and guiding it for 45 parallel and equal motion in all its parts; feed dogs carried by said supporting frame; a space key; and a lever operated by said space key and engaging said supporting frame.

50 10. In a typewriting machine, the combination with front strike type bars, of a universal bar in position to be operated by

said type bars; a sheet metal plate mounted for a bodily motion front and back, and constituting the support for said universal bar; 55 feed dogs carried by said plate; a space key; and an arm operated by said space key and engaging a slot in said plate.

11. In a typewriting machine, the combination with front strike type bars, of a universal bar in position to be operated by said type bars; a horizontal frame mounted in rear of said universal bar and constituting a support for said universal bar; a space key; levers in the base of the machine supporting said space key; a rock shaft or frame extending across the back of the machine and having arms engaged by said levers; and an arm projecting upward from said rock shaft or frame and engaging said 70 universal bar support.

12. In a typewriting machine, the combination of a carriage, a feed rack on said carriage, a feed pinion, an escapement wheel, a shaft for said pinion and wheel, 75 said shaft extending forward through the stationary framework of the machine and having a groove in its forward end, and a slotted plate secured to the stationary framework and engaging in said groove.

13. In a typewriting machine, the combination of a carriage, a feed rack on said carriage, a feed pinion and escapement wheel controlling said rack, a shaft for said pinion and wheel, said shaft extending 85 through a part of the stationary framework, a ribbon vibrator, a guide for said vibrator, and means whereby said guide prevents end-wise motion of said shaft.

14. In a typewriting machine, the combination of a carriage, a feed rack on said carriage, a feed pinion, an escapement wheel, a ribbon vibrator, a detachably mounted guide for said vibrator, and means whereby 90 said guide maintains said feed pinion and escapement wheel in place in the machine.

Signed at Syracuse, in the county of Onondaga and State of New York, this 24th day of August, A. D. 1916.

ARTHUR J. BRIGGS.
